US00D759343S

(12) **United States Design Patent**
Kimura et al.

(10) **Patent No.:** US D759,343 S
(45) **Date of Patent:** ** Jun. 21, 2016

(54) **MACARONI**

- (71) Applicant: **NISSHIN FOODS INC.**, Tokyo (JP)
(72) Inventors: **Ryusuke Kimura**, Tokyo (JP); **Fusaki Kajio**, Tokyo (JP)
(73) Assignee: **NISSHIN FOODS INC.**, Tokyo (JP)
(**) Term: **15 Years**
(21) Appl. No.: **29/543,253**
(22) Filed: **Oct. 22, 2015**

Related U.S. Application Data

- (62) Division of application No. 29/526,971, filed on May 14, 2015, now Pat. No. Des. 745,243, which is a division of application No. 29/488,931, filed on Apr. 24, 2014, now Pat. No. Des. 733,992, which is a division of application No. 29/445,131, filed on Feb. 7, 2013, now Pat. No. Des. 707,419.

(57) **CLAIM**

The ornamental design for a macaroni, as shown and described.

DESCRIPTION

FIG. 1 is a perspective view of a macaroni according to Embodiment 1;

FIG. 2 is a front view of the macaroni according to Embodiment 1;

FIG. 3 is a rear view of the macaroni according to Embodiment 1;

FIG. 4 is a right side view of the macaroni according to Embodiment 1;

FIG. 5 is a left side view of the macaroni according to Embodiment 1;

FIG. 6 is a top plan view of the macaroni according to Embodiment 1;

FIG. 7 is a bottom plan view of the macaroni according to Embodiment 1;

FIG. 8 is a perspective view of a macaroni according to Embodiment 2;

FIG. 9 is a front view of the macaroni according to Embodiment 2;

FIG. 10 is a rear view of the macaroni according to Embodiment 2;

FIG. 11 is a right side view of the macaroni according to Embodiment 2;

FIG. 12 is a left side view of the macaroni according to Embodiment 2;

FIG. 13 is a top plan view of the macaroni according to Embodiment 2; and,

FIG. 14 is a bottom plan view of the macaroni according to Embodiment 2.

1 Claim, 2 Drawing Sheets
